(57) **CLAIM**

The ornamental design for a dental implant, as shown and described.

DESCRIPTION

FIG. 1, shows a front right perspective view the dental implant embodying our new design;
FIG. 2, shows a front left perspective view thereof;
FIG. 3, shows a bottom right perspective view thereof;
FIG. 4, shows a front elevational view thereof;
FIG. 5, shows a side elevational view thereof;
FIG. 6 is a top plan view thereof; and,
FIG. 7, shows a bottom plan view thereof.

The broken lines shown in FIGS. 1-7 depict portions of the dental implant that form no part of the claimed design.
The break lines shown in FIGS. 1-5 depict a break in the claimed design and no part of the break lines or the space between them forms part of the claimed design.
Parallel diagonal lines shading are used to illustrate curvature of the dental implant and show the claimed surfaces and do not connote color.

1 Claim, 4 Drawing Sheets
